(57) **CLAIM**

The ornamental design for a vehicle go button, as shown and described.

DESCRIPTION

This application is related to application Ser. No. 29/714,611, entitled Vehicle Go Button, filed Nov. 25, 2019 and issued on Dec. 22, 2020 as U.S. Pat. No. D905,607, and to application Ser. No. 29/714,634, entitled Vehicle Go Button, filed Nov. 25, 2019 and issued on Dec. 29, 2020 as U.S. Pat. No. D906,208, the entire disclosures of which are incorporated by reference herein. This application is also related to application Ser. No. 29/491,937, entitled Autonomous Vehicle Overall Interior, filed May 27, 2014 and issued as U.S. Design Pat. No. D770,349 on Nov. 1, 2016; to application Ser. No. 29/547,496, entitled Autonomous Vehicle Seat, filed Dec. 4, 2015 and issued as U.S. Design Pat. No. D778,080 on Feb. 7, 2017, which is a divisional of U.S. application Ser. No. 29/491,868, Autonomous Vehicle Seat, filed May 27, 2014 and issued as U.S. Design Pat. No. D755,531 on May 10, 2016; and to application Ser. No. 29/609,747, entitled Autonomous Vehicle Control Button, filed Jul. 5, 2017, which is a divisional of application Ser. No. 29/491,885, entitled Console with Autonomous Vehicle Control Buttons, filed May 27, 2014 and issued as U.S. Design Pat. No. D794,538 on Aug. 15, 2017, the entire disclosures of which are incorporated herein by reference. The FIGURE is a top view of an image for a vehicle go button according to our design.

The features shown in broken lines are environmental only and form no part of the claimed design.
